MULTIPLE PUNCH PRESS

Carlton R. Stevens, Waterbury, Conn.

Original application January 27, 1940, Serial No. 315,978, now Patent No. 2,279,417, dated April 14, 1942. Divided and this application August 29, 1940, Serial No. 354,701

3 Claims. (Cl. 113—38)

This invention relates to presses, and more particularly to a multiple punch press of the eyelet machine type which will be capable of extremely rapid operation.

The present application is a division of my previous application, Ser. No. 315,978, filed January 27, 1940, for Multiple punch presses, now Patent No. 2,279,417, granted April 14, 1942.

One object of this invention is to provide a multiple punch press of the above nature which will be compact in size, light in weight, and of the minimum number of operating parts.

A further object is to provide a machine of the above nature which may be operated with small power and yet which will result in greater production and less wear on the moving parts than with eyelet machines previously used.

A further object is to provide a machine of the above nature having improved means to transfer the products from station to station.

A further object is to provide in a machine of this nature a unitary detachable block in which is mounted the common die holder and its adjusting means, the product transfer means, and the ejecting mechanism.

A still further object is to provide an improved multiple punch press or eyelet machine of the above nature which will be relatively inexpensive to manufacture, simple in construction, ornamental in appearance, and very efficient and durable in use.

With these and other objects in view, which will appear as the description proceeds, there has been illustrated in the accompanying drawings one form in which the invention may be conveniently embodied in practice.

In the drawings:

Fig. 1 is a front assembly view of the improved multiple plunger press.

Fig. 2 is a side view of the same.

Fig. 3 is a vertical sectional view of the same, taken on the line 3—3 of Fig. 1, looking in the direction of the arrows.

Fig. 4 is a plan view on an enlarged scale and partly in section of the bed of the machine, taken on the line 4—4 of Fig. 1.

Fig. 5 is a horizontal enlarged sectional view taken on the line 5—5 of Fig. 1.

Fig. 6 is a vertical enlarged sectional view taken through the die block assembly on the line 6—6 of Fig. 4.

Fig. 7 is a longitudinal vertical enlarged sectional view taken on the line 7—7 of Fig. 4.

Fig. 8 is an enlarged transverse vertical sectional view taken on the line 8—8 of Fig. 4.

Fig. 9 is an enlarged cross-sectional view taken on the line 9—9 of Fig. 4.

Fig. 10 is an enlarged cross-sectional view taken on the line 10—10 of Fig. 4.

Fig. 11 is a vertical sectional view of one of the punch-holding plungers taken on the line 11—11 of Fig. 5.

Fig. 12 is a vertical sectional view of the same taken on the line 12—12 of Fig. 11 at right-angles to the view shown in said figure.

Fig. 13 is a sectional view of the same, taken on the line 13—13 of Fig. 11.

Fig. 14 is a plan view on a greatly enlarged scale of a blank adapted to be stamped by the first punch of this machine, and from which an eyelet or other article may be made.

Fig. 15 is a perspective view of an eyelet which may be formed from the blank shown in Fig. 14 by the operation of the succeeding punches of the machine.

Referring now to the drawings, wherein like reference numerals designate like parts throughout the several views, the numeral 10 denotes a base plate, to which is secured a one-piece machine frame having side uprights 11 and 12, between which extends a top horizontal frame member 13, a pair of vertically spaced-apart intermediate frame members 14 and 15, and a horizontal rear platform 16 located below said frame member 15. The side upright 12 has a pair of spaced-apart horizontal side arms 17 and 18 extending outwardly from its outer side to the right, as viewed in Fig. 1, and in which are located suitable bearings for a vertical transfer cam shaft 21, said bearings being held in place by a pair of removable caps 19 and 20.

The frame side uprights 11 and 12 are provided near their tops with recesses 22 and 23 in which removable bearing blocks 24 and 25, respectively, are secured, as by bolts 26, 26. A horizontal main cam drive shaft 27 is journaled within the bearing blocks 24 and 25, and extends beyond each of the side uprights 11 and 12.

The shaft 27 carries a pair of tight and loose pulleys 28 and 29, respectively, at the left of the upright 11 viewed in Fig. 1. Provision is made of a spur gear 30 and a bevel gear 31 mounted on the shaft 27 outside of the upright 12. A bevel gear 32 is mounted on and secured to the upper end of the vertical shaft 21 and is in mesh with the bevel gear 31. Below the side arm 18 another bevel gear 33 is secured to the lower end of the vertical shaft 21 and meshes with a bevel gear 34 secured to the right-hand end of a horizontal ejector cam shaft 35 (Fig. 1), which ex-

tends beyond the upright 12 below said arm 18. The shaft 35 is journaled in a pair of detachable bearing blocks 36 and 37 secured, as by bolts 38, in a pair of recesses 39 and 40, respectively, provided in the uprights 11 and 12 adjacent the base plate 10. By means of the above construction it will be seen that the vertical shaft 21, the main drive shaft 27, and the ejector cam shaft 25, together with associated pulleys, gears, and other parts, may be readily removed as units from the machine frame for adjustment, repair, or replacement.

Strip feeding mechanism

The "eyelets" (Fig. 15) formed in this machine are adapted to be blanked out from a coil of strip metal 41 wound on a reel 42 supported on a bracket 43 (Fig. 2), said strip being fed from the reel 42 at the front of the machine to a scrap take-up reel 44 supported on a bracket 45 at the rear of the machine. The take-up reel 44 is rotated from the ejector cam shaft 35 by means of a round belt 46 which runs over a small pulley 47 secured on said shaft 35, and a large pulley 48 mounted on a short shaft 49 supported by the rear bracket 45, said belt being in friction-driving engagement with the take-up reel 44 in the usual manner.

The metal strip 41 is adapted to be advanced in timed relation with the machine operation by a pair of cooperating vertically spaced rollers 50 and 51 (Fig. 2) suitably journaled in a bracket 52 mounted on the platform 16. Intermittent feed is given to the strip 41 by means of an elevated crank disc 53, a link 54, and a pawl 55, which is adapted to engage a ratchet wheel 56 secured to the shaft 57 of the roller 51, in the usual well-known manner. The crank disc 53 is secured to a spur gear 58 which is in mesh with the spur gear 30.

In order to maintain the gears 30 and 58 in proper mesh and take up backlash or looseness therebetween due to wear, the gear 58 is mounted on a shaft 59 (see Figs. 2 and 3) which is journaled in an eccentric bushing 60 rotatably mounted in an enlarged section of the frame side upright 12. The bushing 60 is fastened in any desired adjusted position by a set screw 61, and is provided with an enlarged manipulating head 62 by which it may be rotated to shift the shaft 59 and with it the gear 58 toward and away from the gear 30 to adjust the mesh of their cooperating teeth.

Punch plungers

A plurality of equally spaced-apart punch-holding plungers 63 (in this instance six) are provided. The plungers 63 are circular in cross-section and are adapted to be vertically reciprocated in aligned circular holes 64 and 65 formed in a pair of vertically spaced-apart detachable cross-bars 66 and 67. The cross-bars 66 and 67 are adapted to be removably secured to the intermediate cross-frame members 14 and 15, respectively, as by bolts 68 and 69, respectively, located at the ends of the bars 66 and 67. Provision is also made of two rows of intermediate bolts 70 and 71 which are disposed intermediate the adjacent plungers 63 (Fig. 1). It will be understood that since the plungers 63 and the holes 64 and 65 are circular in cross-section, the wear in their bearings will be reduced to the minimum but may be readily taken up by adjusting the bars 66 and 67 by means of the bolts 70 and 71. This adjustment is made possible by

providing narrow slots 73, 73 lengthwise of each of the bars 66 and 67 (see Fig. 5), respectively, the slots 73 extending vertically through the respective bars and opening into each of the plunger-bearing holes 64 and 65. Any wear experienced between any plunger 64 and its corresponding hole 64 or 65 may thus be compensated for by tightening the respective bolt 70 or 71 to force the adjacent portion of the bar 66 or 67 tightly against the respective plunger. Moreover, due to the removability of the cross-frame members 14 and 15, by loosening the bolts 68 and 69, the cross-bars 66 and 67 will be easily accessible for repairs or replacement.

Punch lifters

As most clearly shown in Figs. 3 and 5, provision is made of a plurality of equally spaced-apart punch-lifting plungers 74 (six on this instance) to correspond with the punch-carrying plungers 63 previously described. The plungers 74 are also circular in cross-section and are adapted to be vertically reciprocated in aligned circular bearing holes 75, 76, and 77 formed in vertically spaced-apart cross-bars 78, 79 and 80. The cross-bars 78, 79 and 80 are bolted, respectively, to the top frame member 13, the intermediate frame member 14, and the intermediate frame member 15 by bolts 81, 83, and 85 respectively (Figs. 3 and 5) at the ends of the bars 78, 79 and 80. Bolts 84 and 86, respectively, disposed intermediate adjacent plungers 74 in the bars 79 and 80 are also provided to secure said bars to the respective frame members 14 and 15. For the purpose of adjusting the bars 79 and 80, to take up any wear which may occur between the walls of the holes 76 and 77 and the plungers 74, the bars 79 and 80 may be provided with slots 72 (see Fig. 5), similar to the slots 73 in the bars 66 and 67, supra.

The corresponding pairs of punch-holding plungers 63 and lifting plungers 74 are secured together by six horizontal knee-pieces 87, respectively, each of which is adjustably clamped at its rear end about the plunger 74, by a bolt 82 and secured at the front end to the punch-holding plunger 63 by a bolt 88, so that the corresponding plungers 63 and 74 will move in unison and may be adjusted lengthwise relatively to each other. The plungers 74 are each frictionally engaged by the inner end of a plug 89 slidably in the top cross-bar 78, said plugs 89 being arranged in pairs, each pair being engaged at their outer ends by the opposite ends of a strap 90 (Figs. 1 and 3) which is pressed forwardly to force the plugs 89 inwardly against the respective pair of plungers 74 by an adjustable coil spring 91 reacting between the head of the bolt 92 screw-threaded into the cross-bar 78, and passing through the strap 90. Manual rotation of the bolt 92 will adjust the tension of the spring 91 and thus control the friction on the adjacent plungers.

Each of the punch lifting plungers 74 is provided with a horizontal cam-engaging lifter finger 93 clamped, as by a bolt 94, about one of the plungers 74 and extending therefrom forwardly to a point above the main drive shaft 27 in position to be engaged by one of five up-stroke cams 95 on said shaft 27.

Each of the punch-holding plungers 63 has a plug 96 provided with a hardened end 97 seated in a hole 98 in the upper end of said plungers 63 in position to have its hardened end 97 en-

gaged by one of five downstroke cams 99 on the shaft 27. The remaining right-hand finger 93 (Fig. 1) and plunger bumper head 97 at the blanking station are adapted to be similarly engaged by cams 100 and 101 respectively. The cams 95, 99, 100, and 101 are all mounted on the shaft 27 and are keyed thereto by a common elongated key 102. The cams are adapted to be held in proper position lengthwise on the shaft 27 by means of a tapped spacing collar 103 which is adapted to force said cams to the right against an enlarged section 104 on said shaft 27.

Each plunger head 96 is arranged to be moved lengthwise in the plunger 63 by means of a wedge member 105, to adjust the downward throw of said plunger (see Figs. 11, 12, and 13). Each wedge member 105 passes through a slot 106 formed in its plunger 63, and in so doing passes by a tongue 107 extending downwardly from the lower end of the plug 96. A set screw 108 screw-threaded through one side of each plunger 63 engages the wedge member 105 and clamps its against the tongue 107 and forces the latter against the portion of the plunger opposite the screw.

Punches

At the first operating station of the press, a blanking punch 109 is secured in the usual manner in the lower end of the first plunger 64 which is actuated by the cams 100 and 101 (at the right—Fig. 1). The second punch 110 forms a cup, the next two punches 111 and 112 elongate the shank 113 and partly form the head 114 of the eyelet (see Fig. 15), the fifth punch 115 completes the head 114, and the last or sixth punch 116 pierces the closed end 116a of the eyelet shank 113.

The last five punches 110, 111, 112, 115, and 116 are actuated by the five pairs of cams 95 and 99, described above.

Dies

The blanking punch 109 cooperates with a blanking die 117 (Figs. 7 and 9) which comprises a flat plate over which the strip 41 is fed by the feed rollers 50 and 51. The strip 41 in passing over the die 117 is guided by a slidable guide plate 118 which is held in place by a one-piece metal stripper plate 119. A blank 120 (Fig. 14) is formed by the cooperation of the blanking punch 109 and die 117, and is adapted to be carried down through said die 117 into a carrier disc or transfer block 121 which is seated in a transfer slide 122 and is positioned therein by a vertical pin 123 and a pair of horizontal threaded studs 124 and 125 (see Fig. 9).

Removable die plate holding block

The five succeeding dies 126, 127, 128, 129, and 130 cooperate respectively with the punches 110, 111, 112, 115, and 116, and are all made cylindrical and mounted in a one-piece common die plate 131 (see Fig. 7), each of said dies being retained therein by a horizontal friction plug 132 (see Figs. 8 and 10). Each friction plug 132 is spring-pressed against its respective die by a coiled spring 133 which reacts between the plug 132 and a short set screw 134 screw threaded through one side edge of the common die plate 131. The die plate 131 is removably mounted in a die block 135 and is adapted to be slid transversely thereof in a dovetail recess 136. The die block 135 seats at its ends upon a pair of upwardly facing shoulders 137 and 138 respectively, which are provided at the front of the side uprights 11 and 12. The

die block 135 which extends from the upright 11 to the upright 12 is detachably secured to the machine frame by a pair of threaded bolts 139 which pass transversely through the die block 135 and are screw-threaded into the horizontal platform 16. Moreover, it will be noted that the die block 135 (Figs. 3, 6 and 10) has a pair of strips 135a set into its upper surface at each side of a longitudinal groove 157 formed therebetween above the dovetail recess 136 therein. This construction is for the purpose of facilitating the manufacture and assembly of the machine, and it will be understood that when once in place the strips 135a will remain permanently in the die block 135.

The die holding plate 131 is normally adapted to be disposed in the dovetail recess 136 substantially intermediate the front and rear of the die block 135, and is held in operating position by a pair of spacing bars 140 and 141 (Figs. 3, 6, and 10) provided at the front and rear of said plate 131, said bars also being transversely removable from the die block 135.

In order to transversely adjust the die plate 131 along with the dies 126—130 inclusive carried thereby in the die block 135 to bring said dies into accurate alinement with their corresponding punches, provision is made of a pair of spaced-apart horizontal screws 142 and 143 located on the front of the die block 135, said screws being threaded through a pair of vertical depending lugs 144 and 145 respectively (Figs. 1, 4, and 10). The lugs 144 and 145 are secured to the die block 135 by screws 146, 146, respectively, upon which they may swing downwardly to the positions shown in dotted lines in Fig. 1 to permit the forward removal of the common die plate 131 and the spacing bars 140 and 141 from the die plate holding block 135. The screws 142 and 143 pass through tapped holes in the ends of the lugs 144 and 145 into engagement with the spacing bar 140, and said screws are adapted to be held securely in place by lock nuts 147.

Mechanism for adjusting common die plate

As clearly shown in Fig. 6, the die plate 131 is adapted to be adjusted forwardly and rearwardly to aline the dies 126—130 with the corresponding punches by means of a pair of long horizontal screws 148 and 149, which pass through the die block 135 from the front to the rear and screw-threaded into a pair of vertically disposed rear fingers 150. The fingers 150 are secured at their lower ends to the die block 135 by horizontal screws 151, and have screws 152 screw-threaded through their upper ends to engage the rear surface of the rear spacing bar 141. Lock nuts 153 are provided on the respective screws 152 to hold them permanently in operating position. By means of this construction, it will be seen that adjustment of the die plate 131 may readily be made from the front of the machine by turning the screws 148 and 149. A coiled spring 154, seated in a recess 155 formed in the rear of the die block 135 surrounds each of the screws 148 and 149 and reacts between the end 156 of the recess 155 and the respective vertical finger 150 to urge the latter rearwardly.

Transfer mechanism

The die plate holding block 135 is provided with a longitudinal groove 157 upon its upper surface in which the transfer slide 122 is adapted to be reciprocated in timed relation with the machine operation to transfer the products from one cooperating set of punches and dies to the

next succeeding set. On the first stroke of the slide the blank 120 will be carried by the disc 121 from its punched-out position under the blanking die plate 117 to a position under the second punch 110 to be acted upon thereby. The product formed at this second station in cooperation with the die 126 will be engaged by the free ends of a pair of elongated resilient product transfer fingers 158 and 159 which are secured at their other ends to the reciprocating transfer slide 122, and during each reciprocation of said slide, the product will be advanced along the die plate 131 to a position below the next succeeding or third punch 111.

Similar cooperating pairs of fingers 160 and 161, 162 and 163, 164 and 165 will grip and transfer the products at the succeeding punches and dies 112, 113, 114, and 127, 128, 129 respectively (3rd, 4th, and 5th stations). The front fingers 158, 160, 162 and 164 are inclined rearwardly from the front side wall 188 of a longitudinal extending slot 167 formed in the top of the transfer slide 122, and the rear opposing fingers 159, 161, 163, and 165 are inclined forwardly from the rear side wall 188 of the slot 167.

The products formed by the punch and die 116 and 130 at the last or sixth station are adapted to be blown along the longitudinal slot 167 to the left, as viewed in Fig. 4, and allowed to fall through an oval-shaped hole 169 formed in the die block 135 and from which extends a downwardly inclined conveyer tube 170 to guide said products into a suitable container (not shown).

The scrap piercings resulting from the last station are adapted to fall through the last die 130 into an opening 171 (Fig. 10) provided in the die block 135, and are guided by a downwardly inclined tube 172 into another suitable container (not shown).

An opening 173 is formed in the die block 135 beneath the blanking punch 109 to receive a cylindrical die if the same is desired, but in the present instance, said opening is filled by a plug 174.

Ejecting mechanism

Beneath the dies 126—130 inclusive (at the second to the sixth stations), the die block 135 is provided with holes 175, 176, 177, 178, and 179 (see Fig. 7) which are adapted (as in also the hole 173 beneath the blanking punch 109, in case a die is located at this station), to slidably receive a like number of product ejecting plungers. In this instance, only four product ejecting plungers 179, 180, 181, and 182 are required to produce the eyelet 113 (shown in Fig. 15), and said plungers are provided with suitable ejecting rods 183, 184, 185, 186, respectively, which are adapted to extend upwardly and through the respective dies 126, 127, 128, and 129 to eject products therefrom and raise them into the path of the respective transfer fingers described above. Hardened metallic bumper plugs 187 are located in the enlarged upper ends of each of the holes 175, 176, 177 and 178 to form seats for the respective dies 126—130 inclusive.

The ejecting plungers 179—182 inclusive, and with them the ejecting rods 183—186 inclusive, are adapted to be raised into product-ejecting positions in timed relation with the machine operation by means of four elongated cams 188, 189, 190, and 191 respectively. Each of said cams 188—191 inclusive is split as at 192 (see Fig. 3) and is clamped upon the ejector cam shaft 35 by means of a screw 193. The ejecting plungers

179—182 inclusive are frictionally engaged by the inner ends of four horizontal rods 194 and 195 (see Fig. 6) arranged in two pairs, and having their front outer ends engaged by horizontal plates 196 (one for each pair). Each plate 196 is adapted to be forced inwardly to press the pair of rods 194 and 195 rearwardly against the respective plungers 179—182 inclusive by a screw 197, which passes through the plate 196 and screw threads into the die block 135. A spring 198 (see Fig. 6) may be provided to react between the head of the screw 197 and the plate 196 if desired to increase the friction of the ejector plunger.

The transfer slide 122 is arranged (Figs. 1 and 4) to be reciprocated in timed relation with the machine operation by means of a horizontal plate cam 199 secured on the vertical shaft 21. The cam 199 is adapted to alternately engage a pair of vertical eccentric rollers 200 and 201 secured to an auxiliary slide bar 202 slidable on a supporting member 203 mounted on and fastened to the side arm 18 of the upright frame 12 and the bearing cap 20 thereof by depending bolts 204 and 205 respectively. The roller 200 (see Fig. 7) is rotatably mounted on an eccentric bushing 206 through which extends a vertical bolt 206a, which serves to fasten the bushing 206 to the bar 202. A handle arm 207 extends laterally from the bushing 206 so that the latter may be manually rotated after the bolt 206a is first loosened to effect an adjustment in the position of the center of the roller 200, and thus control the reciprocating stroke of the auxiliary slide bar 202, and through it the stroke of the transfer slide 122 to which it is detachably connected.

In order to provide a readily detachable connection between the auxiliary slide bar 202 and the transfer slide 122, provision is made of a link 208 which is secured, as by a pin 209 and screw 210, to the slide bar 202, and by a pin 211 to the slide 122, respectively. By means of this construction it will be seen that the loosening of the screws 210 permits the removal of the pin 211 from the slide 122 to readily disconnect the latter from the slide bar 202.

In order to permit longitudinal adjustment of the auxiliary slide bar 202, it has dovetail edges (Fig. 2) which fit into a dovetail slot 212 formed in the supporting member 203, and a gib 213 is provided along the front edge of said slide bar 202 for use in taking up wear—said gib 213 being adapted to be pressed transversely against said slide bar 202 by means of three screws 214. Provision is also made of a stop screw 215 at the right-hand end of the supporting member 203 to limit the movement of the slide bar 202, said screw 215 being threaded through an end plate 216 secured to the end of the bearing cap 20 by screws 217.

Stripping mechanism

Product stripping means now to be described are provided at each of the punches 110, 111, 112, 115, and 116, inclusive (see Fig. 7). At the punch 110 the stripping means comprises a spring-pressed pin 218, which is located within and extends downwardly from the punch 110 to release the product therefrom in a well-known manner. At the last or piercing station, the product is stripped from the punch 116 by a plate 219 (Figs. 1, 4 and 7) which is secured to the die block 135 by screws 220 and overlies the transfer slide 122 to close the top of the slot 167 therein at this point. The plate 219 insures the passage of the product toward the oval-shaped hole 169 by a blast of compressed air which is forced through

holes 221 provided in a tube 222 extending transversely over the slide 122 at this point (see Figs. 1, 4, 6, and 10). The tube 222 may be connected to a source of compressed air (not shown) by a hose 223, and is fastened to the die block 135 by a loop strap 224 and screws 225.

The product stripping means associated with each of the intermediate punches 111, 112 and 114 comprises eyelet head-forming sleeves or thimbles 226, 227 and 228 surrounding said punches, respectively (see Fig. 7). The sleeves 226, 227 and 228 are slidably mounted on the stem portions of the punches 111, 112, and 113, respectively, and each is held in place thereon by a flat spring strap or stripper fork 229 (Figs. 3 and 7) which extends rearwardly to a vertical bracket 230 (Fig. 3), which is secured by screws 231 to the rear surface of the platform 16. The straps 229, as they extend forwardly, pass under a horizontal bar 232 secured to the underside of the intermediate frame member 15, which bar carries a plurality of adjusting screws 233 (one for each strap 229), extending downwardly therefrom for engaging said strap 229 to adjustably limit the upward movement thereof. The straps 229 are bifurcated at their forward ends 234 to straddle annular grooves 235 formed on the thimbles 226, 227 and 228. At the extreme forward ends of the straps 229, provision is made of inclined arms 236 (Figs. 1 and 3) secured to the cross-bar 67 by the bolts 71, and extending downwardly from the bar 67 to engage the bifurcated ends 234 of the straps 229 and act as stops while the work is being released from the punches 111, 112 and 115.

Friction brake for transfer slide

At the left-hand end of the machine (Figs. 1, 4, and 6) a horizontal bracket 237 (Figs. 1, 4, and 7) extends across the die block 135 above the transfer slide 122, and is secured to the die block 135 by bolts 238. A friction pad 239 (Fig. 7) engaged by a pair of rods 240 connected together by a strap 241 is pressed downwardly by a screw 242, screw-threaded into the bracket 237, and said pad 239 is adapted to engage the slide 122 to form a drag and prevent sudden movement thereof. An intermediate bracket 243 (Figs. 1, 4, 8, and 9) formed integral with the blanking punch stripper plate 119, is secured to the die block 135 by bolts 244. A friction pad 245, similar to the pad 239, is provided under the bracket 243 and is adapted to be pressed down against the transfer slide 122 by a pair of rods 246 (Fig. 9) connected together by a strap 247, and which is engaged by a screw 248 screw-threaded into the bracket 243.

Operation

The operation of the present invention is in most respects similar to that of the standard eyelet or multiple plunger presses now on the market. The drive shaft 27 is rotated continuously through a belt, not shown, from any suitable source of power by means of the tight pulley 28. The drive shaft 27 rotates a punch and lifter cams secured thereto to reciprocate the punches toward and away from the dies. Through the spur gears 30 and 59 the crank disc 53 is rotated to actuate the strip feeding rollers 50 and 51, and cause the strip 41 to be fed under the blanking punch 109 at the first station. Through the bevel gears 31 and 32, the vertical shaft 21 is rotated to actuate the transfer slide-reciprocating cam 199 for transferring the products from station to station. 75

Through the bevel gears 33 and 34 the lower shaft 35 is driven to rotate the ejector cams 188, 189, 190 and 191, and thereby actuate the ejecting plungers 179-182 and rods 183-186. 5 A continual flow of completed products (in this instance eyelets) are thus caused to drop out of the tube 170, and surplus scrap from the strip 41 is removed from the machine by the tube 172 and coiled up on the take-up roll 44.

10 Among the advantages of the present invention may be mentioned the detachable bearing blocks 24 and 25 which permit the removal as a unit of the shaft 27, spur gear 30, bevel gear 31, and the punch-actuating cams on the shaft 27. Moreover, the auxiliary slide bar 202, the vertical shaft 21, the cam 199, the bevel gears 32 and 33, and the rollers 200 and 201 may also be removed, as a unit, by first detaching the bolts 204 and 205, the bearing caps 19 and 20, 15 the screw 210, and the connecting link 208.

A further advantage is that the die block 135 and all of its associated parts may be readily removed, as a unit, by the simple operation of first loosening the bolts 139 and disconnecting 20 the screw 210. The unit so removed comprises the die block 135, the die plate 131, the slide 122, the stripper plate 119, the carrier disc 121 and transfer fingers on the slide 122, and the ejector plungers and rods and associated parts 25 mounted on the die block 135. This construction greatly facilitates the making of changeovers, repairs, adjustments and replacements. Moreover, should it be desired to merely remove the common die plate 131 and the dies held 30 therein as a unit, the screws 146 only will be loosened and the lugs 144 and 145 may be swung 35 downwardly out of the way.

Another important advantage of the present invention is that all moving parts are arranged 40 for ready removal for replacement, repair, or adjustment. Moreover, being light in weight, though sturdy in construction, the improved machine may be operated at a relatively high speed without excessive wear upon its moving parts or 45 the bearings therefor. Being relatively simple in construction, a machine of the above nature will be comparatively inexpensive to manufacture and operate.

While there has been disclosed in this specification one form in which the invention may be embodied, it is to be understood that this form is shown for the purpose of illustration only, and that the invention is not to be limited to the specific disclosure, but may be modified and embodied in various other forms without departing from its spirit. In short, the invention includes 50 all the modifications and embodiments coming within the scope of the following claims.

Having thus fully described the invention, 55 what is claimed as new and for which it is desired to secure Letters Patent is:

1. In a multiple punch press, a plurality of reciprocable punches providing a series of operative stations, a reciprocable transfer slide to transfer work articles from station to station, a plurality of elongated spring fingers mounted on the slide including means to grip the articles during transfer movement of the slide, a cam for reciprocating said slide, a pair of rollers on said slide arranged to engage the cam on opposite sides thereof to shift the slide in opposite directions, an eccentric mounting for one of said rollers, means mounting said eccentric for turning movements to vary the position of the

slide, means for turning the eccentric, and means for clamping the eccentric in adjusted positions.

2. In a multiple punch press, a plurality of reciprocable punches providing a series of operative stations, a reciprocable transfer slide to transfer work articles from station to station, a plurality of elongated spring fingers mounted on the slide including means to grip the articles during transfer movement of the slide, a cam for reciprocating said slide, a pair of rollers on said slide arranged to engage the cam on opposite sides thereof to shift the slide in opposite directions, a bolt mounted on the slide, an eccentric bushing mounted to turn on the bolt and forming a bearing for one of the rollers, means on the bushing for turning it to adjust the position of the roller and vary the position of the slide, and means for clamping the bushing in adjusted positions.

3. In a multiple punch press, a plurality of 20

reciprocable punches providing a series of operative stations, a reciprocable transfer slide to transfer work articles from station to station and comprising a slide and an auxiliary slide 5 bar, a plurality of elongated spring fingers mounted on the slide including means to grip the articles during transfer movement of the slide, a detachable link connecting the bar with the slide and forming the sole connection between them, a cam for reciprocating said transfer slide, a pair of rollers on the bar arranged to engage the cam on opposite sides thereof to shift the slide in opposite directions, an eccentric mounting for one of the rollers, means 10 mounting said eccentric for turning movements to vary the position of the slide, means for turning the eccentric, and means for clamping the eccentric in adjusted positions.

CARLTON R. STEVENS.
